UNITED STATES PATENT OFFICE.

ELLSWORTH EMLEY, OF LANCASTER, OHIO.

DESIGN FOR A GAGE-TOOL.

SPECIFICATION forming part of Design No. 28,398, dated March 22, 1898.

Application filed November 8, 1897. Serial No. 657,886. Term of patent 7 years.

To all whom it may concern:

Be it known that I, ELLSWORTH EMLEY, a citizen of the United States, residing at Lancaster, in the county of Fairfield and State of Ohio, have invented and produced a certain new and original Design for a Gage-Tool; and I do declare the following to be a full, clear, and exact description of the invention, such as will enable others skilled in the art to which it appertains to make and use the same.

My invention relates to a design for a gage-tool. It relates to the entire configuration of the tool.

My invention relates particularly to the design for a gage-tool, as illustrated in the accompanying drawings, in which—

Figure 1 is a plan view of a gage-tool, illustrating my design. Fig. 2 is an obverse view of the same.

The leading features of my design are set forth in the accompanying description.

The design comprises a plane plate in the form of an oblong rectangle having parallel edges and plane parallel ends arranged at right angles to said parallel edges. One of said parallel edges is formed with a series of pointed teeth arranged at regular predetermined distances, the terminal tooth at one

end of the series being beveled inwardly, and also from one side to give it a fine or needle point, and the corresponding tooth on the same parallel edge and at the opposite end being formed oblong, as shown. This oblong or elongated end tooth is provided with a V-shaped notch, and two corresponding V-shaped notches appear on the opposite parallel edge of the tool, as shown. A series of transverse parallel equidistant gage-slots, each one terminating in a circular orifice, are formed on the edge opposite to said teeth, and a series of orifices, as shown, are formed at certain predetermined distances in the body of the plate.

Having thus fully described my invention, what I claim as new and useful, and desire to secure by Letters Patent of the United States, is—

The design for a gage-tool, substantially as herein shown and described.

In testimony whereof I hereunto affix my signature in presence of two witnesses.

ELLSWORTH EMLEY.
